UNITED STATES PATENT OFFICE.

JOHN GEARON, OF BELOIT, IOWA.

TOOL-HANDLE.

SPECIFICATION forming part of Letters Patent No. 235,426, dated December 14, 1880.

Application filed May 3, 1880. (No model.)

To all whom it may concern:

Be it known that I, JOHN GEARON, of Beloit, in the county of Lyon and State of Iowa, have invented a new and useful Improvement 5 in Mode of Attaching Handles to Axes, Hammers, and other Tools, of which the following is a specification.

My invention relates to tools such as have heretofore been provided with eyes for the reception of the wooden handles, such as axes, hammers, picks, adzes, and similar tools.

The accompanying drawings illustrate the manner of applying the invention to an ax.

Figure 1 is a side view of an ax embodying my improvements. Fig. 2 is a section taken in the line $x x$ of Fig. 1. Fig. 3 is a view of the head of the ax. Fig. 4 is a perspective view of one of the bars used for securing the handle to the ax.

Similar letters of reference indicate corresponding parts.

A represents an ax, which, instead of being formed with an eye, is provided with two recesses, $a a$, on the exterior, at points opposite each other corresponding with the point at which the eye is usually located. These recesses a are slightly tapering, and their sides are of dovetail form.

B B represent two bars, each of which is tapering and of dovetail form, corresponding exactly in shape and dimensions with the recesses $a a$ for a distance equal to the width of the ax. Beyond this distance, in a direction toward the handle, the bars are rounded and screw-threaded on their exterior surface, and provided each with a concavity or recess, b , on the interior surface. The outer end of each bar is provided with a flange, d , for engage-

ment with a shoulder, c , at the outer end of the recess a in the ax.

The handle E has a convexity to correspond with the annular recess b , and a shoulder to correspond with the reverse shoulder of the bars B, so that the handle E and bars B may be securely attached together.

To attach the handle to the ax the bars B B are placed in the recesses $a a$ of the ax. The handle E is then inserted between the bars and the parts are secured by a ring-nut, G, screwed outside of the bars and handle, as shown in Figs. 1 and 2. By this means the handle is held firmly and securely in place, and may readily be tightened when necessary, or removed and replaced when desired.

Having thus described my invention, I claim as new and desire to secure by Letters Patent—

1. The combination, with a tool having dovetail side grooves, a , and shoulder c , of two tapering bars, B, shaped to fit said recesses, and having an end flange, d , that engages the shoulder c , as described.

2. The bars B, formed with the recesses b and flanges d , in combination with the ax or other tool having recesses a and shoulders c , and with a handle, E, substantially as herein described.

3. The combination, with externally end-threaded bars B, having recesses b , of the handle E and ring-nut G, said handle and bars having reverse locking-shoulders, as shown, and for the purpose specified.

JOHN GEARON.
